UNITED STATES PATENT OFFICE.

CHARLES H. PFEIL, OF CHICAGO, ILLINOIS.

DESIGN FOR A FINGER-RING.

SPECIFICATION forming part of Design No. 30,647, dated May 2, 1899.

Application filed March 8, 1899. Serial No. 708,283. Term of patent 7 years.

To all whom it may concern:

Be it known that I, CHARLES H. PFEIL, a citizen of the United States of America, and a resident of Chicago, in the county of Cook and State of Illinois, have invented a certain new and original Design for Finger-Rings, of which the following is a specification, reference being had to the accompanying drawings, forming a part thereof.

Figure 1 is a top plan of a finger-ring made according to my new design. Fig. 2 is a perspective view of same.

The leading or material feature of my design consists of the representation of a pair of eagle-heads in reversed positions, each with the beak open and disposed toward the other, forming a socket between both beaks, in which

the gem is seated. Each eagle-head 2 has its superior jaw 3 of the beak disposed toward the inferior jaw 4 of the other beak, so that 20 the gem 1 is thus surrounded by the four jaws. The body 5 of the ring is integral with both heads, forming a continuation at the base of each.

What I claim as new, and desire to secure 25 by Letters Patent, is—

The design for a finger-ring, substantially as herein shown and described.

Signed by me, at Chicago, this 6th day of March, 1899.

CHARLES H. PFEIL.

Witnesses:

ALFRED MELTZER,
WM. R. RUMMLER.
